Primary Examiner — Mimosa De(74) *Attorney, Agent, or Firm* — Gardner Linn(57) **CLAIM**

The ornamental design for body support structures (seats), as shown and described.

DESCRIPTION

FIG. 1 is a perspective view of body support structures (seats) showing our new design;

FIG. 2 is a front elevation thereof;

FIG. 3 is a rear elevation thereof;

FIG. 4 is a left side elevation thereof, wherein a right side elevation is a mirror image of the left side elevation; and,

FIG. 5 is a top plan view thereof.

A bottom view of the body support structures (seats) constitutes no part of the claimed design.
